COMBING MACHINE

John William Nasmith, Heaton Mersey,
Manchester, EnglandApplication January 26, 1942, Serial No. 428,265
In Great Britain March 7, 1941

3 Claims. (Cl. 19—121)

The present invention relates to combing machines for textile fibres, of the Nasmith type, and in which machines the top comb moves to and from the detaching roller position, descending to penetrate the fibre tuft being dealt with and again lifting from such tuft, and disengaging therefrom.

I have found it in practice desirable to ensure that the top comb should not entirely disengage from the fibre tuft until the separation of the latter is entirely made in the operation of the machine, and the object of this invention is to provide means for ensuring that the top comb shall remain engaged in the fibre tuft until the separation of the latter is completely ended before such comb lifts. For this purpose the invention comprises in combination with an oscillated top comb-bearing arm a member which permits the fall of such arm to penetrate the tuft and effects its lift on its retrogressive movement from the usual detaching rollers, with means for varying the point at which, on such retrogressive movement, the lift is effected. As in the second model of Nasmith combing machine one top comb operating shaft serves to oscillate the top combs in a plurality of machine heads.

The invention, with suitable and practical details of these arrangements, will now be described with reference to the annexed drawing, which is a section through a machine head.

Referring to the drawing, W indicates the nipper shaft; D, d the detaching rollers, T the top comb shaft oscillated in the manner known for the operation of a top comb shaft independently of the machine nipper in the second model of Nasmith combing machine, and L a further shaft operated from a cam in the headstock. The top comb arm 1 is pivoted on a pin 2 oscillating along an arc 10 and fixed in the lever 3 keyed on the shaft T. The arm carries a bowl 4 which rests on the upper surface 5 of a second arm 6 pivoted at 7 in the lever 8 keyed on the shaft L. On the arm 6 is an adjustable incline 9, and it also carries a broad-headed set screw 11 resting on a bowl 12 running on a pin 13 fixed in the framing. The parts are so arranged and designed that when the top face 5 of the arm 6 is horizontal the top comb is practically at the proper depth and in proper relation to the detaching roller D. The set screw 11 serves to correct any slight inaccuracy. At that point in the stroke of the machine when the comb should penetrate the nipper tuft, the arm 6 is stationary, and the inclines 9 in all the heads of the machine are adjusted just to touch the bowls 4. All having been adjusted they may all be moved simultaneously a little one way or the other to vary the moment of penetration. This provides a convenient and powerful means of altering the amount of waste, quite independently of the nipper adjustment. The bowl 60

4 having left the incline 9 continues its forward course along the face 5 of the lever 6, and during this time this latter lever is slightly withdrawn by the operation of the shaft L, so that when the bowl 4 in its return movement arrives at the point 5 where it left the incline 9 the latter is no longer in that original position. The bowl must therefore move a little further before coming into contact with the incline and lifting. Thus the top comb remains down a little longer than it would otherwise do, this ensuring the complete separation of the detached tuft before lifting of the comb. In this way the point of penetration is rendered quite independent of the point when the top comb lifts, and may be varied either way.

I claim:

1. In a combing machine for textile fibres, detaching rollers, a top comb bearing arm oscillated to and from the roller position, a control member permitting the fall of such arm at a constant point at commencement of its forward movement towards the detaching rollers and effecting the subsequent lift thereof at the end of its retrogressive movement, and means for altering by the control member the point of lift of the arm, at each stroke of the machine, in relation to the point of its previous fall, with consequent variation of length of top comb path between the forward and retrogressive movements of such top comb.

2. In a combing machine for textile fibres, detaching rollers, a top comb bearing arm oscillated to and from the detaching roller position, a further and control arm oscillated in a path approximately parallel to that of the first arm but independently thereof, an inclined face upon one such arm and a co-acting part upon the other arm with consequent fall at a constant point and lift of the top comb bearing arm in its oscillation, and means for altering the position at which the control arm lifts the top comb bearing arm at each stroke of the machine in relation to the point of previous fall of the top comb bearing arm.

3. In a combing machine for textile fibres, detaching rollers, a top comb bearing arm oscillated to and from the detaching roller position, a further and control arm oscillated in a path approximately parallel to that of the first arm but independently thereof, an inclined face upon the control arm and a co-acting part upon the top comb bearing arm with consequent fall at a constant point and lift of the latter arm in its oscillation, and an oscillated shaft connected to the control arm, with consequent variation of position of the inclined face borne by the control member at each complete stroke of the machine between the point of fall and the point of desired lift of the top comb bearing arm.

JOHN WILLIAM NASMITH.
